ICE REFRIGERATOR

Harry B. Imes, Louisville, Ky., assignor to William H. Cloud, Louisville, Ky.

Application February 1, 1936, Serial No. 61,997

19 Claims. (Cl. 62—31)

This invention relates to ice refrigerators, or refrigerators of that type using ice in block or cake form as the active refrigerant.

One object of the invention is to provide a refrigerator having a novel and improved construction of ice supporting and air cooling and circulating means whereby the cooling action of the ice is utilized to the highest degree, the cooled air most effectively distributed and the general efficiency of refrigerators of this type materially increased.

Another object of the invention is to provide a construction of refrigerator which ensures a more perfect insulation of the ice compartment from the outer atmosphere and a regular and even melting of the block or blocks of ice employed as the active refrigerant.

Still another object of the invention is to provide a novel construction of ice supporting grid embodying spaced air cooling and circulating channels in direct contact with the ice whereby more uniform and efficient cooling and circulation of the internal surfaces of the refrigerator and of the contained air is obtained.

Still another object of the invention is to provide a novel construction of ice supporting grid and drip pan having coacting surfaces for cooling and circulating the air in the most efficient and advantageous manner while at the same time preventing access of drip water or condensation moisture to the goods storage compartment of the refrigerator.

Still another object of the invention is to provide novel means for automatically forming individual cubes of ice for domestic uses from the refrigerant block of ice resting on the grid and permitting the removal of such cubes from the main block of ice in a ready and convenient manner and as desired.

Still another object of the invention is to provide means whereby ice supporting grids provided with or without cube formers may be interchangeably mounted in the refrigerator casing.

Still another object of the invention is to provide a grid carrying a cube former which is removable as a unit with the grid or separately therefrom.

Still another object of the invention is to provide a novel construction of drip pan for catching and discharging all drip water and moisture of condensation and discharging the same from the refrigerator.

Still another object of the invention is to provide a construction of ice supporting grid, drip pan and coacting parts which are readily ac-

cessible for cleaning, repairs and other purposes.

Still another object of the invention is to provide a construction and arrangement of parts increasing the general utility, convenience and efficiency of refrigerators of this class.

With these and other objects in view, the invention consists of the features of construction, combination and arrangement of parts, herein-after fully described and claimed, reference being had to the accompanying drawings, in which:—

Fig. 1 is a horizontal section through the ice compartment of the refrigerator looking down upon the ice supporting grid.

Fig. 2 is a similar view looking from below toward the ice supporting grid.

Fig. 3 is a central vertical transverse section on line 3—3 of Fig. 1.

Fig. 4 is a front-to-rear vertical section taken substantially on line 4—4 of Fig. 1.

Fig. 5 is a similar view taken substantially on line 5—5 of Fig. 1.

Fig. 6 is a horizontal section on a reduced scale taken on line 6—6 of Fig. 3.

Figs. 7, 8, and 9 are fragmentary bottom plan views of the grid showing positions of the cube former fastening means.

Fig. 10 is a fragmentary bottom plan view of the grid with the cube former removed therefrom.

Fig. 11 is a similar view of the removed cube former.

Fig. 12 is a vertical transverse section on line 12—12 of Fig. 1 showing the cube former as it appears in normal position.

Fig. 13 is a similar view showing the cube former dropped to permit of the severance of the formed cubes from the ice block and showing the manner of forming the cubes from the ice block.

Figs. 14 and 15 are detail front-to-rear sections through the grid and cube former, Fig. 14 showing the appearance of the parts with the cube former in normal position and Fig. 15 the appearance of the parts when the cube former is dropped for insertion of an ice pick or other tool for severing the ice cubes.

Figs. 16 and 17 are detail front-to-rear sections showing the drip pan in normal and depressed positions.

Fig. 18 is an enlarged detail view showing one of the sets of supporting links for the drip pan in the opened up positions they occupy when the pan is depressed.

Fig. 19 is a detail section on line 19—19 of Fig. 1, illustrating a detail of construction.

Fig. 20 is a view of a portion of the baffle plate.

In the exemplified embodiment of my invention, I provide a casing 1 of suitable general form and construction and which as shown embodies an upper chamber or compartment 2 to hold blocks or cakes of ice used as the refrigerant and a lower chamber or compartment 3 for the reception of the foodstuff or other goods to be stored and maintained in proper condition. The body of the refrigerator is of double-walled type, comprising an outer wall 4 and an inner wall 5 suitably spaced apart and packed therebetween with suitable insulation 6. The casing may be provided with a doorway at the front coextensive in width and depth with the chambers 2 and 3 and adapted to be closed by a single door 7, or separate and independent doorways and doors for giving access to the respective chambers may be employed. The form and construction of the chamber may in these and other respects be made in accordance with any of the various forms and general construction of refrigerator casings in common use.

The walls 4 and 5 may be of sheet metal or other suitable material, and those portions of the walls 4 and 5 which form the chamber or compartment 2 are preferably spaced a greater distance apart than those wall portions forming the chamber or compartment 3, so as to reduce the length and width of the compartment 2 with respect to that of the compartment 3 and so as to enable the amount of insulation 6 placed between the wall portions forming the compartment 2 to be increased in order to prevent too rapid melting of the ice contained therein and to ensure economy in the use of ice. To this end, the portions of the inner walls 4 forming at least the sides of the compartment 2 may be set inwardly or offset from the underlying portions of the walls 5, as indicated at 8. This wall construction, in connection with certain arrangements of the internal parts of the refrigerator, as hereinafter described, also provides for the formation of vertical air flues 9 at the sides of the upper portion of the chamber 3.

At the sides at least of the bottom of the chamber or compartment 2 are disposed supporting members 10 in the form of channel irons, the outer flanges of which are welded or otherwise secured to the walls 5 and the inner flanges of which have fitted thereon inverted U-shaped or channeled cap pieces 11. To the body portions of these supports 10 are fastened a grid or shelf 12 forming with the members 11 a support for the ice 13 contained in block or cake form in the compartment 2. This grid or shelf comprises an open rectangular or oblong rectangular frame consisting of a front rail 14, a rear rail 15 and side rails 16 united at the frame corners in any suitable manner. Between the rails 16, in parallel relation to each other and to the rails 14 and 15, extend a row of hollow grid bars or tubes 17, the rearmost one of which is arranged in close relation to the rail 15, while the forward one of which is spaced a distance from the rail 14 to provide an intervening opening 18. The hollow grid bars or tubes may in practice be of any suitable construction, but, as shown in the present instance, each grid bar or tube consists of a pair of sheet metal channels soldered, riveted or otherwise suitably united to provide a bar or tube of rectangular form in cross-section. The upper surfaces of these grid bars or tubes are arranged in the same plane as the cap pieces 11 to form with the latter supports on which the ice block or cake rests. The arrangement of the bars or tubes

in spaced relation provides a row of vertical transverse cooling and air circulating passages 19. Each bar or tube 17 is open at its opposite ends to provide air inlets 20 communicating with the flues 9 and each bar or tube 17 is provided in its underside with a longitudinally extending slot 21 extending to equal degrees in opposite directions from the transverse center of the tube. A comb-shaped baffle plate 22 extends vertically beneath the grid centrally and from front to rear thereof the distance between a partition plate 23, separating the front tube 17 from the opening 18, and the rear grid rail 15 and is provided with two series of long and short projections 24 and 25 which extend upwardly respectively into the spaces 20 between the tubes 17 and into the bodies of the tubes themselves through the slots 21. By this construction the air channel of each tube 17, and each space 19 between adjacent tubes, is divided by a central partition into two channels located on opposite sides of the center of the casing and communicating respectively through the inlets 20 at each side of the refrigerator with the flues 9 and through the slots 21 forming spaced air discharge outlets, with the central portion of the chamber or compartment 3 beneath the grid for the circulation beneath the grid and within the chamber 3 of currents of air in the manner hereinafter described.

The opening 18 at the front of the grid is designed for the reception of an ice cuber 26. This consists of a box or receptacle of oblong rectangular form and constructed to fit snugly beneath said opening 18 and to abut in applied position against the rails 16. The cuber is formed with one or more rows or any desired arrangement of cube forming pockets 27 open at their upper ends and closed at their sides and bottoms and provided in their closed bottoms with small drain outlets 28. This cuber is so arranged that the pockets 27 thereof are disposed, like the spaces 20, beneath the block or cake of ice 13 supported by the grid. In the operation of the refrigerator, as the ice melts and descends under its weight, portions of the bottom of the ice cake project downward into the spaces 19 in the form of ribs 29 and portions of the ice cake project downwardly into the cube forming pockets 27 in the form of projections 30, which ribs 29 and projections 30 are caused, by the melting of adjacent portions of the ice due to the relatively warmer metal surfaces, to descend into the spaces 20 and pockets 27 in spaced relation to and free from engagement with all surfaces thereof. Therefore, after the cake of ice has been in use for a certain period and melted to a certain degree, the ribs 29 are produced which extend into the spaces 20 and form cooling portions of ice whereby the currents of air traveling through said spaces 20 are effectually cooled, while at the same time projections 30 of ice are produced within the pockets 27 which may be separated from the block of ice, when they reach a suitable size, to produce ice cubes for domestic use.

The cuber 26 is detachably fastened in position by a novel construction of supporting and fastening means. This supporting and fastening means comprises a centrally disposed operating lever 31 pivoted to the underside of the cuber at or near its center, and with which are pivotally connected latch bars 32 movable through guides 33 on the underside of the cuber and having their outer end portions 34 forming latch

members engageable with keeper slots 35 in keeper members 36 secured to the underside of the grid rails 16, the free end of the lever 31 being provided with a finger piece 37 and the 5 construction being such that by movement of the lever in opposite directions the latch bars may be moved inwardly or outwardly to retract or project the latch members. Each latch bar carries adjacent to the latch member a locking 10 wedge or cam 38 having a lower inclined surface, and the keeper slots 35 are of sufficient depth to receive these locking wedges or cams. The construction of this supporting and locking mechanism is such as to adapt the cuber to be 15 held in the normal position shown in Figs. 12 and 14, raised against the rails 16, or to be lowered and supported without disconnection from the grid, as shown in Figs. 13 and 15, so as to space the cuber from the rail 14 to form an intervening passage or slot through which a suitable tool, such as an ice pick or the like, as indicated at 39 in Fig. 15, may be introduced for the purpose of severing the cube projections 30 from the ice block 13. By this means it will be 20 seen that whenever projections 30 of suitable size are formed and it is desired to separate any one or more of them from the ice block to form cubes for use, this may be effected by adjusting the locking mechanism from the locking position shown in Figs. 12 and 14, in which the wedges 38 occupy the openings 35, to the depressed supporting position shown in Figs. 13 and 15, in which the latch ends 34 of the latch bars occupy the openings 35 and support the 25 cuber in the depressed condition for the introduction of the tool 39 and severance of the ice cubes. By then further retracting the latch bars the latch members may be withdrawn from the keeper openings 35 to allow the cuber to be removed from the grid for the extraction of the 30 ice cubes. In this manner a novel construction of means is provided for the formation of ice cubes from an ice block automatically through the descent of the block at it melts. 35 The grid 12 may be either fixedly or removably secured in position. In the present instance it is shown as removably secured in position by means of fastening bolts 40 passing through openings in the supporting channels 10 and rails 40 16 of the grid and engaging threaded members or notches 41 integral with or fixed to the rail 16 of the grid. This mode of mounting allows of the interchangeable use of grids with or without cubers, and of the removal of a detachable 45 grid and a cuber as a unit or the removal of the cuber independently of the grid, as will be 50 readily understood.

The construction of that part of the refrigerator forming the ice chamber 2, which is protected by the thickened layer of insulation, and is in communication with the chamber 3 only through the restricted spaces 19 and by conduction through the walls of the grid, ensures, at 55 all times when the door to said chamber is closed, the formation therein of a substantial dead air space which in turn ensures a substantially uniform melting of the ice block or cake, with economy in the use of ice and the effective production of cooling ribs 29 and cube projections 30 of adequate size.

Disposed in the upper portion of the chamber or compartment 3 beneath the grid is a drip or drain pan 42, which pan comprises a bottom plate 43, having upstanding front and rear flanges 44, and a pan-shaped top plate 45 which

fits down between the flanges of the bottom plate and is provided with a downturned hooked rim 46 suitably secured to the flanges 44 of said bottom plate, the two plates being thus disposed in fixed and superposed relation with an intervening air flow duct or channel 47 therebetween. The drip pan thus formed is of less width than the distance between the walls 5 so as to terminate short of the flues 9 and is of sufficient area to completely underlie the grid and to catch 10 all drain water and water of condensation dripping from the grid. The pan may be inclined at a suitable angle of inclination between its front and rear edges for the rearward drain of the moisture and the pan members are provided 15 at the rear with the concentrically arranged drain tubes 48 and 49 which discharge the moisture therefrom into the usual refrigerator drain pipe 50. The pan is pivotally connected at each side and near its rear end to hanger straps 51 whereby it is supported from the grid for up and down swinging movements toward and from the grid, so that when tilted downwardly all portions of the pan and adjacent portions of the 20 grid will be rendered accessible through the front top opening in the refrigerator casing for easy cleaning or repairs whenever required. At a point between its front edge and supports 51 the pan is suspended at each side from hanger brackets 52 on the grid by means of a link member 53 pivoted at its lower end to the pan and a link 54 pivoted at its upper end to the bracket 52 and at its lower end to the upper end of the link 53, the pivotal connections of the link 54 with the parts 53 and 52 being arranged 25 respectively at the lower front corner of the link 54 and at the upper rear corner thereof. On the bracket 52 is a stop member 55 and on each lower link is a finger piece 56 serving also as a stop member. The arrangement of these 30 links is such that when the pan is swung up to normal position, as shown in Fig. 16, the links 54 will lie against the stops 55 and the pivotal connection between the links 53 and 54 will lie 35 in rear of the pivotal connection between the links 54 and the brackets 52, with the finger piece and stop 56 abutting against the link 54, whereby through this off center connection the pan will be locked by the folding links in raised 40 position. The operator by engaging the fingers of the hands with the finger pieces 56, however, may draw the links 53 and 54 forward to a releasing position in which the links will drop down, as shown in Figs. 17 and 18, for an 45 unlocking action and a supporting action in which the pan is held disposed and in an inclined position to allow free access to the pan and other adjacent parts for cleaning or repairs. Formed in the bottom pan section 43 adjacent 50 to and on opposite sides of the transverse center thereof are slots or openings 57, and formed in the upper pan section 45 above and in alignment with the slots 57 are slots or openings 58 communicating with the air flow channel between the pan sections and with the space between 55 the pan and grid. The openings 58 are preferably bounded by upstanding guard kerbs or flanges 58' which permit of the flow of air there-through but prevent the water in the pan section 45 from flowing out therewith. The body portion of the comb-shaped baffle plate or partition 22 previously described depends in the space 60 between the grid and drip pan to a point between the two openings 58, and disposed on opposite sides of this depending portion of the 65

70 75

baffle plate are roof-shaped baffles 59 which overhang the openings 58 in spaced relation thereto. Each of these baffles 59 consists of an upper plate 60 and a lower plate 61 connected in spaced relation thereto, said plates being carried by supports 62 rising from the pan member 45. The plates 60, as shown, lie on opposite sides of the baffle 22 beneath the air outlets 21 of the hollow grid bars or tubes and within the air flow passages or chambers 62 formed between the grid and drip pan, which passages communicate at their sides or outer ends with the flues 9 and through the outlets 21 with the channels of the hollow grid bars or tubes. By this arrangement of the baffles 59 the plates 60 form water sheds to conduct any water of condensation dripping from the grid into the pan 45 and to prevent the same from flowing outward with the air through the passages 58, while the lower plate section 61 of each baffle 59 collects any particles of water condensing thereon into the pan 45 to likewise prevent such moisture particles from passing down through the passages 58. As a result of the described construction and arrangement 25 of the grid and pan, it will be seen that portions of the warm air currents rising from the chamber 3 will flow upward at the sides thereof and through the flues 9 into the channels formed by the hollow grid bars or tubes and into the spaces 30 between said bars or tubes, then inwardly and downwardly through the outlets 21 into the passages 62 and through the passages or openings 58 and 57 back into the chamber 3, while at the same time other portions of the air passing 35 upwardly through the flues, will flow into the spaces 62 and thence downwardly through the openings 59 and 58 back to the chamber 3. In this manner, therefore, the rising warm air from the food chamber will travel upward at the sides 40 or warmer portions of the chamber, thence inwardly and horizontally through the cooling surfaces formed by the grid tube channels and spaces therebetween and by the grid and drip pan surfaces, so that such currents of air will 45 be cooled and the moisture deposited by condensation therefrom caught by the pan, and the cooled currents caused to travel back through the center openings in the pan to the chamber 3 and downward at the center of said chamber 50 where the lowest temperature prevails, thus ensuring the cooling of the air to a maximum extent and its circulation and distribution in the most effective manner about the cooling surfaces and within the chamber 3 to maintain a desired 55 and substantially low constant temperature in said chamber 3. As shown, the channel 47 between the drip pan plates is open at the sides and communicates with the flues 9. If desired, the flanges 44 of the lower end section may be 60 provided with openings 63 for connecting the upper portion of the chamber 3 at front and rear with the channel 47, so that an additional circulation of air at the front and rear of the refrigerator may be obtained through said channel 65 to further cool the air and to facilitate the discharge of collected moisture.

Preferably the upstanding projections 24 of the baffle plate 22 are extended above the level of the upper surfaces of the hollow grid bars or tubes 17 and are engaged by a U-shaped cap piece 64 which extends the full distance from front to rear of the grid and forms an intermediate support for the ice block 13. Finger pieces 65 may be attached to the underside of the cube former to assist in its removal.

From the foregoing description, taken in connection with the drawings, the construction and mode of operation of my improved ice refrigerator structure will be readily understood and it will be seen that the invention provides a 5 structure of this kind in which the most effective cooling of the air by the refrigerant and its circulation is obtained in order to keep the chamber or compartment 3 at a predetermined low temperature, while at the same time a most effective collection and drainage off of all drip water and water of condensation will be obtained and the moisture prevented from dripping down into or injuring foodstuffs stored in the chamber or compartment 3. By the construction of 10 the grid with hollow grid bars or tubes of the character described provision is made for cooling the grid surfaces and bringing the circulating air in contact therewith and in direct contact with portions of the ice whereby maximum cooling of the air in circulation is ensured. This cooling effect is amplified and intensified by the novel construction of the drip pan and its utilization to provide supplemental cooling surfaces and to direct the flow of the air so that a 15 cooling effect of the drip water and water of condensation on the air will also be obtained without danger of the passage of any water into the food containing compartment. Also it will be seen that my invention provides in a very 20 simple and effective way for the production of ice cubes for domestic use in an ice refrigerator and directly from the ice block or cake itself, thus enabling portions of ice in convenient form for many purposes to be supplied to the user. 25 My invention thus provides an ice refrigerator of novel type and having these and many other desirable and important advantages over prior 30 refrigerators of its kind.

It will be understood, of course, that while the 35 structure disclosed is preferred, modifications, other than those shown or suggested, in the form, construction and arrangement of the parts, within the scope of the appended claims, may be made 40 without departing from the spirit or sacrificing 45 any of the advantages of the invention.

What I claim is:—

1. An ice refrigerator comprising a casing, an ice supporting grid detachably mounted in the casing, a cube former carried by the grid and mounted thereon for removal therewith from the casing or for removal independently thereof from the casing, and means for raising and lowering the cube former relative to the grid and supporting it in a lowered position.

2. An ice refrigerator comprising a casing, an ice supporting grid mounted in the casing and provided with an opening therein, a cube former detachably mounted on the grid below and in alignment with said opening, and means for raising and lowering the cube former relative to the grid and supporting it in a lowered position.

3. An ice refrigerator comprising a casing, an ice supporting grid mounted in the casing and having an opening therein, a cube former carried by the grid below and in alignment with the opening, and fastening means for detachably connecting said cube former with the grid and for supporting said cube former in a depressed position relative to its normal plane to provide a space thereabove for insertion of a cube severing tool.

4. An ice refrigerator comprising a casing having an upper ice holding compartment and a lower goods containing compartment, an ice supporting 75

grid arranged between said compartments and embodying a series of spaced hollow grid members extending transversely of the casing and having air inlet openings at their outer ends 5 and air outlets in their bottom portions at or near the center thereof, a drip pan disposed beneath the grid and spaced from the sides of the goods compartment to provide vertical air flues at said sides of the compartment, said pan having air 10 openings extending therethrough adjacent to and on opposite sides of the center thereof and connecting the central portion of the goods compartment therebelow with the space between the grid and drip pan, and baffling means in said 15 space and in the spaces between the grid members and extending into the air outlets of the grid members to form passages connecting the hollow grid members with the air flues and openings in the pan.

20 5. An ice refrigerator comprising a casing, an ice supporting grid mounted therein and having an opening at the front thereof, a pocketed cube forming element mounted on the grid below and in alinement with said opening, and fastening 25 devices for supporting the cube forming element in operative position or supporting it in a relatively lowered position.

6. A refrigerator having an ice supporting grid, a cube forming element provided with pockets, 30 and means for securing said element to the grid, said securing means being movable to a position to space the element from the grid without releasing it therefrom and to a position for releasing the element entirely from the grid.

35 7. A refrigerator having an ice supporting grid provided with an opening therein, a cube forming element provided with pockets disposed beneath the opening in the grid, and fastening means for securing the cube forming element to the grid, said fastening means embodying parts movable to dispose the cube forming element in spaced relation to the grid without releasing it therefrom and to a position for releasing said element for detachment from the grid.

45 8. A refrigerator comprising a casing, an ice supporting grid arranged therein and having a series of hollow parallel grid members provided with end air inlets and centrally located bottom air outlets for the circulation of air therethrough, 50 a drip pan disposed beneath the grid and having air circulating openings therein, a baffle arranged between said openings and the grid members and also extending into the latter to divide portions of the casing into air flow channels communicating with said openings, and baffles disposed 55 between the grid and drip pan and above the openings in the latter for directing drip water and moisture away from said openings.

9. A refrigerator comprising a casing, an ice 60 supporting grid in said casing, a drip pan arranged in the casing beneath the grid and pivotally mounted at its rear end for swinging movements upwardly and downwardly toward and from the grid, and linkage connections between 65 the front of the drip pan and the casing adapted to fold and unfold in the up and down movements of the pan and to lock the pan in raised position.

10. An ice refrigerator comprising a casing, an 70 ice supporting grid within the casing provided with a series of parallel hollow grid members forming air channels having air inlets at one end and air outlets in their bottom portions near the center thereof, a drip pan disposed beneath the 75 grid and provided with air circulating openings

therein adjacent to and on opposite sides of the center thereof, a partition disposed between said openings and having portions projecting upwardly into the hollow grid elements and into the spaces therebetween to form flow channels on opposite sides of the center of the refrigerator, and baffle devices disposed between the grid and drip pan and guarding the openings therein against the entrance of drip water and moisture thereto.

11. An ice refrigerator comprising a casing having an upper ice containing compartment and a lower goods containing compartment, an ice supporting grid disposed between said compartments and having hollow ice supporting members spaced to provide passages therebetween and forming air channels having air inlets at the sides of the refrigerator and bottom air outlets at the center of the refrigerator, a drip pan arranged beneath the grid in spaced relation thereto and having central air openings therein below said air outlets of the ice supporting members, the said parts being arranged to provide warm air flues at the top of the sides of the goods containing compartment with which said air inlets and passages communicate, a cube former carried by the grid, and baffling means associated with said air spaces and passages to direct the air from the flues therethrough.

12. An ice refrigerator comprising a casing 30 having an upper ice containing compartment and a lower goods containing compartment, an ice supporting grid disposed between said compartments and having hollow ice supporting members forming air conductors and spaced to provide passages therebetween, said members having air inlets at their ends located at the sides of the refrigerator and having their bottom walls formed with air outlets located at the center of the refrigerator, a drip pan arranged beneath the grid in spaced relation thereto and having central air openings therein below said air outlets of the hollow ice supporting members, the said parts being arranged to provide warm air flues at the top of the sides of the goods containing compartment with which said air inlets and passages communicate and baffling means arranged beneath said central air outlets of the hollow ice supporting members and above said central air openings in the drip pan for directing air flowing from the 40 said outlets to said openings.

13. An ice refrigerator having an ice supporting grid mounted therein and embodying a frame and parallel hollow ice supporting grid bars extending between opposite sides of the frame and forming air circulating conductors, said bars having air inlets at their ends and centrally disposed air outlets in their bottom portions.

14. An ice refrigerator comprising a casing having an upper cooling compartment and a lower 60 goods containing compartment, an ice supporting grid separating said compartments and embodying hollow parallel grid members extending from side to side of the grid, said grid members forming air conductors provided with air inlets at 65 their outer ends communicating with the top portion of the goods containing compartment at opposite sides of the latter and said grid members having air outlets in their bottom portions at or near the center thereof, and baffling means disposed beneath said outlets to direct air flowing from said outlets downwardly at the center of the goods containing compartment.

15. An ice refrigerator comprising a casing, an ice supporting grid mounted therein and embody-

- ing spaced grid members, said grid having an opening at the front thereof, a pocketed cube forming element arranged beneath the grid in alinement with said opening, and fastening means 5 adjustably and detachably connecting said cube forming element with the grid to adapt it to be supported in a depressed position with relation to the ice supporting surface of the grid without removal therefrom or to be detached there- 10 from for removal.
16. A refrigerator having an ice receiving compartment and a goods holding compartment, an ice supporting grid therein separating said compartments and embodying hollow ice support- 15 ing members forming air ducts having air inlets and outlets communicating at different points with the goods containing compartment, and a cube former carried by the grid and adjustable therein to a position to expose the cubes for sep- 20 aration from an ice cake resting on the grid.
17. A refrigerator having an ice receiving compartment and a goods holding compartment, an ice supporting grid therein between said compartments embodying parallel hollow ice sup- 25 porting grid members forming air cooling and circulating ducts and separated to form air cooling spaces between said members, the members being provided with air inlets and outlets com- municating at different points with the goods

holding compartment, and a cube former carried by the grid and adjustable thereon from a cube forming position to a position below the same to expose the cubes for separation from an ice cake resting on the grid.

18. A refrigerator comprising a casing having an ice receiving compartment, and an ice supporting grid embodying a plurality of spaced parallel ice supporting members arranged in spaced relation and forming air cooling spaces therebetween, each of said members being of tubular form to provide an air cooling and circulating channel open for the inlet of air at the ends of the member and provided in its underside at or adjacent to the center thereof with air outlets 18 for the discharge of the air.

19. A refrigerator having an ice supporting surface comprising relatively stationary and adjustable sections, said adjustable section being provided with depending pockets for the automatic formation of cubes from portions of a block of ice resting on said surface by descent of the ice as it melts, the adjustable section being mounted for movement relative to the stationary section below its normal ice supporting position 20 to permit of the use of an implement for severing the cubes from the block.

HARRY B. IMES.
